Application November 13, 1935, Serial No. 49,624
Renewed October 29, 1937

28 Claims. (Cl. 230—26)

This invention relates to compressors and particularly to unloading means therefor.

In compressors with mechanically operated valves it has been proposed to unload the compressor variably by varying the timing of the inlet valves and similar schemes have been proposed for compressors having suction operated (sometimes called "automatic") inlet valves.

As applied to the latter class of compressors, unloading may be effected in either of two ways (1) holding the inlet valves closed commencing at a variable point in the suction stroke and continuing until the piston reaches the same point in the compression stroke, and (2) holding the inlet valve open for a variable period during the initial portion of the compression stroke. Broadly stated, the two schemes are equivalent in that they vary the weight of gas compressed per cycle (a cycle comprising a suction and ensuing compression stroke) but the second method is usually preferred, because cylinder pressure approximates suction pressure during the unloaded portion of the cycle and the tendency toward leakage and thermal losses consequently is less.

The present invention is applicable to compressors having suction operated inlet valves, and is applicable to either type of unloading operation just mentioned. Obviously the timing of the valve controllers relatively to the cycle would be different in the two cases, and the controllers in one case would hold the inlet valves closed and in the other would hold the valves open, but the basic principle of the mechanism herein described and claimed would be the same in the two cases.

As stated, the second scheme of operation is preferred, and to simplify the disclosure, the invention will be described as embodied in a system of this type.

The invention proposes a control unit driven in timed relation to the compressor crank shaft, and acting through liquid pressure lines to deliver suitably timed impulses to unloader motors which control the automatic inlet valves. A single means responsive to receiver pressure (or equivalent demand indicator) progressively varies the duration of the impulses relatively to the strokes in which unloading occurs. Thus the unloading action may be effective progressively in any degree from full load to no load.

According to the preferred arrangement the inlet valve unloader motors are normally biased to no load position and the impulses by their

variable duration establish a variable loaded condition in response to demand.

The controller contains not only means for generating the necessary pressure impulses but also servo-motor means for controlling the duration of such impulses, in response to receiver pressure or other demand indicator. In this way a self-contained and highly responsive mechanism is provided. Such units may be manufactured to control any desired number of working spaces making up a single stage or multi-stage compressor. Such units may be timed simply by setting the actuating cams on the cam shaft.

The invention will now be described as applied to a two stage, two cylinder double-acting compressor having cranks set at 90°. Such a compressor has four working spaces and the inlet valves for the four spaces operate at 90° intervals. Consequently the unloaders for the four working spaces operate at similar intervals.

In the drawings,—

Fig. 1 is a plan view of a compressor of the type stated, with the invention applied.

Fig. 2 is a head-end elevation thereof.

Fig. 3 is a fragmentary section transverse to the axis of a cylinder through the center line of one of the two low pressure head end inlet valves with its unloading motor.

Fig. 4 is a section through the center line of the same inlet valve, the plane of section being taken in the direction of the axis of the cylinder.

Fig. 5 is a sectional plan view of a controller for controlling the inlet valves of four working spaces. The plane of section is indicated at 5—5 on Fig. 6.

Fig. 6 is a section on the line 6—6 of Fig. 5 (i. e. through the impulse generator for the low pressure head end inlet valve unloader).

Fig. 7 is a section on the line 7—7 of Fig. 5.

Referring first to Figs. 1 and 2, the foundation or bed of the compressor is indicated at 11, the low pressure frame at 12, the high pressure frame at 13 and the crank shaft at 14. The crank shaft 14 turns in bearings in frames 12 and 13 and as usual reciprocates pistons one in the low pressure cylinder 15 and another in the high pressure cylinder 16. The drive from crank shaft to pistons is conventional, and is effected through the usual cranks (here set at 90° to each other) connecting rods, crossheads and piston rods, one of each for each piston. These parts are not visible in the drawings because they are enclosed. A portion of the low pressure piston appears at 17 in Fig. 4.

The compressor may be driven by any suitable means, but a synchronous motor of the fly-wheel type is conventionally indicated at 10.

- 5 The intake or suction 19 leads to pairs of inlet valves having bonnets 21 on the lower side and at both ends of the low pressure cylinder 15. The low pressure cylinder discharges through the pairs of automatic discharge valves having bonnets 22 on the upper side and at both ends of 10 the low pressure cylinder 15, and thence through intercooler 23 to the inlet valves having bonnets 24 on the upper side and at both ends of the high pressure cylinder 16. The high pressure cylinder discharges through the automatic discharge valves having bonnets 25 on the lower side and at both ends of the high pressure cylinder, and thence through pipe 26 to the receiver 27, from which the compressed gas is delivered through pipe 28 to any point of use.
- 20 The inlet valves will be described as of the "reed" or "feather" type, described and claimed in the patent to Nordberg 1,570,392, January 19, 1926, and are structurally similar for both cylinders. The discharge valves may be, and preferably are of the same type, though any suitable discharge valve, automatic or other, may be used. Discharge valves are necessary, but their construction is not a feature of the invention.

- Each inlet valve is provided with an unloader 30 motor whose function is to hold the valve open for a variable portion of the discharge stroke (in the corresponding working space) and then permit the valve to close. These motors will be described in detail hereinafter. Each is controlled by a corresponding impulse generator and a timer contained in housing 31. The drive shaft 32 of this mechanism is driven from crank shaft 14 at the same angular velocity through sprocket chain 33. Receiver pressure is transmitted by 40 pipe 34 to the timer mechanism in housing 31, the timer mechanism serving to vary the duration of the generated impulses in response to variations of receiver pressure. There is an impulse generator for each group of similarly timed inlet 45 valves, and pipes 35 transmit their impulses to the unloader motors of respective groups. In the drawings the pipes 35 are differentiated by the legends l. h. e. for the low pressure head end, l. c. e. for the low pressure crank end, and similarly h. h. e. and h. c. e. for the two ends of the high pressure cylinder.

Referring now to Figs. 3 and 4 which show one of the head end inlet valves in place in the low pressure cylinder, it will be observed that the cylinder 15 has a head 36 with cooling jacket space 37, and that the cylinder barrel is cored to produce the usual jacket, portions of which appear at 38, and an inlet passage 39 leading to the inlet valves from the inlet connection 19 located 55 at mid-length of the cylinder (see Fig. 1). In Fig. 4 the piston 17 is shown at the head end dead point. Note that the rings 41 approach but do not overtravel the inlet port 42.

Seated in rib 43 surrounding port 42 and sealed thereto by gasket 44 is the grid-like valve seat member 45. The seat member 45 is held in place by studs 46 threaded in bonnet 21 and engaging in thrust the inverted V-shaped yokes 47. One 70 end of each stud is swiveled in the corresponding yoke 47, as indicated at 49. The yokes 47 are cast as a unit with ring 48 and are connected to the seat member 45 by machine screws 51. The construction is such that if the nuts 52 which 75 hold the bonnet 21 in place on the cylinder be

removed, the whole valve assembly may be withdrawn as a unit.

Connected to seat member 45 by studs 53 and spaced therefrom by the filler pieces 54 is a grid-like guard 55. The bars 56 of guard 55 overlie the port slots 57 in seat 45 and confine reed valve units each comprising a long narrow valve plate 58 and associated blow-spring 59. This is essentially the construction of the Nordberg patent above identified.

To unseat the reed valve elements 58 during the unloading operation, there is provided a yoke 61 carrying two comb elements 62, whose teeth 63 project through the ports 57 in the seat 45 and in their inner position toward the axis of the cylinder, hold all the reed valves 58 unseated. The yoke 61 is carried on a plunger 64 which is guided in a hub 65 integral with the bonnet 21.

Fixed on the upper ends of the plunger 64 is a rectangular yoke 66 whose upper end collides with a combined spring seat and stop 67 to limit the retreat of the plunger 64 in an outward direction. The spring seat 67 is mounted in the outer end or neck of a sleeve 68 which is threaded into an aperture in the bonnet 21 and carries threaded to it a closure cap 69. The yoke 66, and consequently the plunger 64, is urged inwardly, that is toward the center of the compressor cylinder by a coil compression spring 71 which rests between a flange on the spring seat 67 and the outer end of the yoke 66. The yoke 66 encloses a plunger or piston 72 provided with packing grooves, as clearly indicated in Figs. 2 and 4. This plunger works in a cylinder 73 finely encircled by yoke 66 and formed as a separate unit. Cylinder 73 is positioned in the bonnet 21 by means of lugs 74 and 75. The cylinder 73 is clamped in a recess in the bonnet 21 by the sleeve member 68, which is threaded into the bonnet 21 and engages lugs 74 and 75 to hold the cylinder 73 in place. Inward movement of plunger 64 is limited by collision of the upper end of yoke 66 with the upper end of cylinder 73. A set screw 76 prevents the sleeve 68 from working loose.

The impulse pipe, which in the case of the valve illustrated in Fig. 4, is the pipe 17 i. n. e. communicates by means of a nipple 77 threaded into the bonnet 21 and penetrating the lug 75, with a passage 78 formed in lug 75 and leading to the space in cylinder 73 below the piston 72. The spring 71 urges the plunger 64 in an unloading direction, and pressure fluid admitted against the inner end of the piston 72 may overpower the spring 71 and move the plunger 64 in a loading direction, that is, in a direction to retract the 55 comb teeth 63 out of engagement with the valves 58.

Briefly stated, in the absence of pressure acting on the plunger 72 the spring 71 moves the combs in to hold the inlet valves unseated. The admission of pressure fluid against the plunger 72 retracts the combs and permits the inlet valves to perform their normal functions.

Broadly considered, this is typical of any automatic inlet valve with means operative alternatively to hold the inlet valve constantly open or to permit it to close and function normally. The arrangement is peculiar in the fact that the mechanism is biased by the spring 71 in an unloading direction and loading is produced by the admission of pressure fluid to the actuating piston.

The mechanism which develops against the plunger 72 timed fluid pressure impulses will now be described with reference to Figs. 5, 6 and 75

7. The pressure fluid is conveniently, but not necessarily oil. In the following description oil is disclosed as the pressure transmitting fluid, but without any limiting implication. The housing 31 described in connection with Figs. 1 and 2 is an oil sump or reservoir through which the shaft 32 extends, the shaft being mounted in bearings 81 and being sealed against oil leakage at 82. The shaft 32 carries four actuating cams 10 which correspond to the inlet valves for the four working spaces of the compressor. These cams are angularly spaced according to the timing of the inlet valves of the four working spaces of the compressor, that is to say, the cam 83 l. c. e. is set at 180° from the cam 83 l. h. e. Similarly the cam 83 h. h. e. is at 180° from the cam 83 h. c. e. The first two cams which operate respectively the crank end and head end unloaders for the low pressure cylinders, are displaced 90° from the second set of cams which operate, respectively, the head end and crank end unloaders for the high pressure cylinders. Each of these cams operates an impulse mechanism and since these are identical a description of a single one 25 will suffice. Fig. 6 shows the impulse mechanism for the low pressure head end inlet valves.

While the cams 83 have been differentiated as to the particular inlet valve which they control it is deemed unnecessary to apply the distinguishing letters to the apparatus actuated by the cams, it being understood that these various mechanisms are duplicates.

The cams 83 each operate a corresponding oil displacing plunger 84. Each is reciprocated in the cylinder by the cam and each is urged toward the cam by a coil compression spring 85. 86 is a valve which is normally closed and which is provided to insure filling of the plunger space with oil, since the presence of compressible gas 40 in the cylinder would affect the timing. The space below the plunger 84 communicates with a corresponding impulse pipe 35, the particular impulse pipe illustrated in Fig. 6 being that connected to the low pressure head end inlet valve, 45 as indicated by the legend 35 l. h. e. Communication from the space below the plunger 84 to the pipe 35 is afforded by the passage 87. Interposed between the passage 87 and the sump within the casing 31 is a combined admission and 50 spill-back valve 88. This is a simple poppet valve seating against flow from the passage to the sump, urged in a closing direction by a coil spring 89, and capable of being unseated by thrust exerted through stem 91 which is in telescopic thrust relation with the pilot of the valve 88. The stem 91 is held in alignment with the valve by its telescopic engagement and is guided to reciprocate longitudinally through the guide bearing 92. It is normally retracted to permit 55 the valve 88 to seat by means of a coil compression spring 93 which reacts between the guide plate 92 and a spring seat 94 which is adjustable on the stem 91 by means of a nut 95. A shaft 96 is rotatable in bearings 90 within the housing 60 31, the shaft 96 being parallel with the shaft 32.

The shaft 96 carries a number of aligned eccentrics 97, one corresponding to each of the plungers 84, and journaled on each eccentric 97 is a 65 rock lever 98, one end of which is in thrust engagement with the upper face of a lug 99 on the corresponding plunger 84, and the other end of which is in thrust engagement with the adjustable tappet 101 on the corresponding stem 91. 70 In the example shown, the tappet 101 is threaded

on the push rod 91 and vertical adjustment relatively to the push rod is afforded in this manner.

As the plunger 84 is depressed its related rock lever 98 turns in a counterclockwise direction, permitting a related upward movement of the 5 corresponding valve 88. Rotation of the shaft 96 in reverse directions raises or lowers eccentric 97 and thus varies the point in the downward stroke of the plunger 84 at which the spill back valve 88 will seat. When the valve 88 does seat 10 the oil displaced by the plunger 84 will flow through the corresponding pipe 35, in this case 35 l. h. e. and cause retraction of the unloading plunger of the corresponding inlet valve. Each plunger 84 displaces more than sufficient oil to 15 move a corresponding plunger 72 through its full stroke, and it is therefore necessary to provide for each passage 87 a relief valve 102. This relief valve takes the form of a poppet valve opening away from the passage 87 and discharging 20 into a manifold 103 which forms part of a pressure accumulator hereinafter described.

The valve 102 is urged to its seat by a light coil compression spring 104. The seat for the valve 102 is formed in the bushing 105 which is 25 mounted in a cavity in the base of the housing 31 and held in place by a plug 106 threaded into the base and engaging the bushing 105 through pressure equalizing thrust ball 107 and an associated cap member 108.

The excess oil discharged to the passage 103 which receives excess oil from all the plungers 84, leads to an accumulator cylinder 109 (see Figs. 5 and 7). This accumulator cylinder is provided with a plunger 111 which is spring loaded by a coil compression spring 112. Pressure in the accumulator assists in holding valves 102 seated, so in effect this is a loaded relief valve. The load on the spring 112 is adjusted by shifting the spring seat 113. Adjustment is effected 40 by turning the threaded rod 114, which is swiveled at 115 in the seat 113 and which is threaded in the closure 116. A lock nut 117 is provided to preserve the adjustment. To prevent the development of fluid pressure above plunger 111, a 45 vent 119 is provided.

Oil entering the chamber 109 forces the piston 111 upward against the resistance of spring 112 and excess oil discharges to the oil sump through a relief port 118. The effect is to establish and maintain, during the operation of the device, a supply of oil under pressure in the accumulator 109, and this oil is supplied from the excess delivered by the various impulse generators. The valves 102 prevent back flow to the passages 87 55 and maintain the isolation of the passages 87 from one another.

Formed in the base of the housing 31 is a cylinder which receives a differential piston 121. This offers at its lower end 122 a piston head 60 of large effective area and affords by means of a shoulder or offset 123 an annular piston head of smaller effective area. The piston is guided, and the upper end of the working space for the annular piston head 123, is closed by a guide 65 sleeve 124 fixedly mounted on the base of the housing 31.

The piston 121 has an axial bore in which is mounted a balanced piston valve having an upper head 125 and a lower head 126 separated by an 70 intervening groove. The valve is balanced by means of a port 127 extending from the space above the upper head 125 to the space below the lower head 126. A passage 128 leads from the accumulator space 109 to the working space above 75

the annular piston head 123, and a passage 129 leads from this space through the piston to the space around the reduced middle portion of the piston valve. The space above the upper head 125 communicates with the oil sump in housing 31 by way of passage 131. The upper valve head 125 has very slight lap at its upper and lower edges over a port 132 connected by passage 133 with the space below the large piston head 122 of the piston 121. A bushing 130 threaded into a bore in the piston 121 serves as a limit stop for the piston valve.

It is obvious that if the two opposed working spaces of the piston 121 are connected together 15 the piston will move upward because the larger effective area will predominate. On the other hand, if they are disconnected, and if the larger space be then vented back to the sump, the piston will move downward. The head 125 with 20 its very slight lap on port 132 establishes these connections selectively, and it will be obvious from a consideration of Fig. 7 that the piston 121 will follow the valve head 125 in its upward and downward movements.

25 The piston 121 is provided near its upper end, with rack teeth 134 which coat with a sector gear 135 on shaft 96, which is the shaft on which the control eccentrics 97 are mounted. The position of the valve head 125 is adjusted by means 30 responsive to the demand for compressed air, and in the example illustrated this means is a device responsive to pressure in the high pressure receiver 27. Many different arrangements might be used, but as a simple example, there has been 35 chosen a differential bellows mechanism.

40 Mounted in housings 136 and 137 are metal bellows 138 and a slightly smaller metal bellows 139. The interior of both bellows are subject to pressure in the receiver 27 communicated by way 45 of the pipe 34 (Figs. 1, 2 and 7) and the passages 141 and 142. The bellows act in opposition to each other through a longitudinally shiftable rod 143. The purpose of using two bellows of differential areas is to secure a relatively small effective area with parts of substantial size. While the bellows themselves offer some elastic 50 resistance to displacement it is sometimes desirable to modify this and permit adjustment of the yielding resistance by using a light compression spring 144 whose stress is adjustable by shifting the collar 145 on the rod 143. This spring is shown confined between the end of housing 137 and the collar 145 and the collar may be clamped in adjusted position by means of a set screw 146.

55 Pivoted on a fixed fulcrum at 147 is a bell crank lever 148, one of whose arms is connected to the rod 143 by a link 149 and the other of whose arms is connected to the stem of valve 125 by means of link 151. It will be observed that on 60 rising receiver pressure, and defining direction with reference to Fig. 7, the rod 143 will move to the right, swinging the bell crank 148 clockwise and lowering the valve 125. Since the piston 121 follows the valve the piston will move downward 65 turning the shaft 96 counterclockwise and lowering the eccentrics 97. The lowering of the eccentrics 97 causes the valves 88 to close later in the displacement stroke of their related plungers 84.

70 Since the delivery of pressure to the pressure motors on the inlet valves terminates the unloading action, delay in the closure of the valves 88 increases the unloading action. The shaft 32 is so timed relatively to the crank shaft 14 that 75 each of the cams 83 starts to depress its plunger

84 at such time that each corresponding plunger 72 is raised just prior to the commencement of the discharge stroke in the corresponding working space of the compressor. The range of adjustment afforded by rotation of the shaft 96 is 5 such that in the uppermost position of the eccentrics 97 the valve 88 will be allowed to close with the plunger 84 in its uppermost position. Similarly the eccentrics 97 are in their lowermost position and the valves 88 are not allowed to 10 close throughout the entire downward stroke of the plunger 84. It is apparent, therefore, that the adjustment of the shaft 96 provides progressive adjustment from full capacity to a completely unloaded condition, and the adjustment 15 of the shaft 97 is responsive to variation of receiver pressure through narrow limits determined by the operation of the bellows mechanism.

There is an important consideration affecting the design of the cams 83. The comb blades 63 20 should be so timed in their operation that they engage the inlet valve 58 when the valve is open and prevent the valve from closing, but they should never engage the valve 58 when the latter is closed. The function of the combs is to prevent 25 the valves from moving from an open to a closed position. It is never their function to move the valves from a closed to an open position. Obviously, if the blades 63 come into action only when the valves are open the force which 30 they exert will be minimized and injury to relatively delicate valves will be avoided.

The desired result can be secured by designing the cams 83 in such a way that they produce 35 downward motion of corresponding plungers 84 through more than 180° of rotation of shaft 32. A satisfactory value is 225° of rotation. The unloading action is effected during the discharge stroke. Under full capacity conditions the inlet 40 valves are allowed to remain closed throughout the entire discharge stroke. Under completely unloaded conditions they are held open throughout the entire discharge stroke, and under partial capacity conditions they are held open from the beginning of the discharge stroke to a variable 45 point in the stroke.

Thus the blades assume obstructing position before the end of the suction stroke when the inlet valves are open, and under full load condition are retracted not later than the dead point. 50 The mechanism controlling their retraction should be so flexible as to allow them to remain retracted throughout the discharge stroke or to retract them at any point in the discharge stroke depending on the desired capacity. Having once 55 been retracted they should not again be moved into position to hold the inlet valves open until the inlet valves have been opened by suction. Because of unavoidable clearance in some compressors the inlet valves may not open by suction until 60 the suction stroke has proceeded through a substantial crank angle. To meet this condition plunger 84 may be made active from a point before the end of one suction stroke to a point after the beginning of the next suction stroke. 65

A bypass valve 152, (Fig. 7) which normally is closed, may be opened by turning handle 153, and when open dissipates pressure in the accumulator 109, and passages 87 (since valves 102 will open under predominant pressure in passages 87). 70 As a consequence the compressor will be unloaded.

The invention has a number of important advantages. The unloading means, that is the unloading plungers on the inlet valves, are biased in an unloading direction, making it relatively sim- 75

ple to start the compressor under no load. The use of a liquid link to time the unloading mechanism minimizes lag such as would be occasioned by the use of a compressible medium, and thus insures precise timing. Experience with the device has shown that there is a slight time lag between the start of the downward motion of a plunger 84 and the response of the corresponding plunger 72. This lag appears to be constant for any given installation and was readily compensated for by slightly advancing the cam shaft 32 with respect to the crank shaft 14 of the compressor.

It has heretofore been proposed to operate unloading motors by means of gas compressed by the compressor. This scheme is workable where air is being compressed, but is open to obvious objections when noxious gases are being compressed, because special means must be provided to prevent the slightest leakage.

The unloading means can be applied to existing compressors merely by equipping the inlet valves with the necessary unloading motors and by arranging the impulse and timing unit so that it is driven at the proper rate from the crank shaft of the compressor. The device can be arranged to unload any desired number of working spaces and the cams 83 may be angularly displaced on the cam shaft to conform to any angular spacing of the compressor cranks.

The invention permits progressive unloading from full capacity to a fully unloaded condition and can be arranged to unload different stages of a multi-stage compressor to insure proper division of work between the different stages under all load conditions.

The possibility of adapting the same general control scheme to another known principle of unloading in which the inlet valves are held closed instead of being held open, has been stated.

While one embodiment of the invention has been described in considerable detail, the inventive concept is capable of expression in specifically different mechanisms by the exercise of ordinary mechanical skill.

What is claimed is,—

1. The combination of a compressor of the expandable chamber type adapted to perform successive operating cycles; an unloading device having two positions, in one of which it renders the compressor inoperative and in the other of which it renders it operative; means biasing said unloader toward one of said positions; a pressure motor serving when energized to shift said unloader to the other of said positions; an impulse piston actuated in timed relation to the cycles of the compressor; means establishing a fluid pressure transmitting connection between said impulse piston and said pressure motor; and adjustable means for venting said connection throughout a variable portion of the displacing stroke of said impulse piston.

2. The combination of a compressor of the expandable chamber type adapted to perform successive operating cycles; an unloading device having two positions, in one of which it renders the compressor inoperative and in the other of which it renders it operative; means biasing said unloader toward one of said positions; a pressure motor serving when energized to shift said unloader to the other of said positions; an impulse piston actuated in timed relation to the cycles of the compressor; means establishing a fluid pressure transmitting connection between said impulse piston and said pressure motor; adjustable means

for venting said connection throughout a variable portion of the displacing stroke of said impulse piston; and means responsive to the pressure established by the operation of the compressor for adjusting the last-named means.

3. The combination of a compressor of the expandable chamber type adapted to perform successive operating cycles; an unloading device having two positions, in one of which it renders the compressor inoperative and in the other of which it renders it operative; means biasing said unloader toward the first-named of said positions; a pressure motor serving when energized to shift said unloader to the second-named of said positions; an impulse piston actuated in timed relation to the cycles of the compressor; means establishing a fluid pressure transmitting connection between said impulse piston and said pressure motor; and adjustable means for venting said connection throughout a variable portion of the displacing stroke of said impulse piston.

4. The combination of a compressor of the expandable chamber type adapted to perform successive operating cycles; an unloading device having two positions, in one of which it renders the compressor inoperative and in the other of which it renders it operative; means biasing said unloader toward one of said positions; a pressure motor serving when energized to shift said unloader to the other of said positions; an impulse piston actuated in timed relation to the cycles of the compressor; means establishing a fluid pressure transmitting connection between said impulse piston and said pressure motor; normally closed venting means for said connection; adjustable means for opening said venting means through a variable portion of the displacing stroke of said impulse piston; and means for adjusting the last-named means.

5. The combination of a compressor having a cylinder, a coacting piston, and an inlet valve; unloading means having two positions, in one of which it renders the inlet valve inoperative and in the other of which it permits the inlet valve to operate; means biasing said unloading means to one of said positions; a pressure motor adapted when under pressure to shift said unloading means to the other of said positions; an impulse piston actuated in timed relation to the compressor piston; means establishing a fluid pressure transmitting connection between the impulse piston and the pressure motor; adjustable means for venting said connection through a variable portion of the displacing stroke of said impulse piston; and means for adjusting the last-named means.

6. The combination of a compressor having a cylinder, a coacting piston, and an inlet valve; unloading means controlling said inlet valve and biased to a position in which it holds the inlet valve open; a fluid pressure operated unloader motor associated with said unloading means and adapted when under pressure to shift said unloading means to a position in which it permits the inlet valve to close; an impulse piston actuated in timed relation to the compressor piston; means for establishing a fluid pressure transmitting connection between the impulse piston and the unloader motor; adjustable means for venting said connection through a variable portion of the displacing stroke of said impulse piston; and means for adjusting the last-named means.

7. The combination of a compressor of the expandable chamber type adapted to perform

successive operating cycles; an unloading device having two positions, in one of which it renders the compressor inoperative and in the other of which it renders it operative; means biasing said unloader toward one of said positions; a hydraulic pressure motor serving when energized to shift said unloader to the other of said positions; a hydraulic impulse piston actuated in timed relation to the cycles of the compressor and having a displacement which exceeds the displacement of said hydraulic pressure motor; means for establishing a hydraulic pressure transmitting connection between the impulse piston and said hydraulic pressure motor; a loaded relief valve for permitting flow of excess hydraulic liquid from said connection; and an adjustable means operated in timed relation with the impulse piston for freely venting said connection through a variable portion of the displacing stroke of said impulse piston.

3. The combination of a compressor of the expandible chamber type adapted to perform successive operating cycles; an unloading device having two positions, in one of which it renders the compressor inoperative and in the other of which it renders it operative; means biasing said unloader toward one of said positions; a hydraulic pressure motor serving when energized to shift said unloader to the other of said positions; a hydraulic impulse piston actuated in timed relation to the cycles of the compressor and having a displacement which exceeds the displacement of said hydraulic pressure motor; means for establishing a hydraulic pressure transmitting connection between the impulse piston and said hydraulic pressure motor; a loaded relief valve for permitting flow of excess hydraulic liquid from said connection; adjustable means for freely venting said connection through a variable portion of the displacing stroke of said impulse piston; and means responsive to a pressure established by operation of the compressor for adjusting the last-named means.

4. The combination of a compressor having a cylinder, a coacting piston, and an inlet valve; an unloader having two positions, in one of which it renders said inlet valve inoperative and in the other of which it permits it to operate; means biasing said unloader to one of said positions; a hydraulic pressure motor adapted when subjected to pressure to shift said unloader to the other of said positions; a hydraulic impulse piston actuated in timed relation to the compressor piston and having a displacement which exceeds the displacement of the hydraulic motor; means for establishing a hydraulic pressure transmitting connection between the impulse piston and the hydraulic motor; a loaded relief valve permitting flow of excess hydraulic liquid from said connection; and adjustable means operating in timed relation with the impulse piston for freely venting said connection through a variable portion of the displacing stroke of said impulse piston.

5. The combination of a compressor having a cylinder, a coacting piston and an inlet valve; shiftable means adapted to obstruct the closing movement of the inlet valve; means biasing said shifting means toward obstructing position; a hydraulic unloader motor serving when subjected to pressure to withdraw said obstructing means; a hydraulic impulse piston actuated in timed relation to the compressor piston and having a displacement which exceeds the displacement of the unloader motor; means for establishing a hydraulic pressure transmitting connection be-

tween the impulse piston and the unloader piston; a loaded relief valve permitting flow of excess hydraulic liquid from said connection; adjustable means operating in timed relation with the impulse piston for freely venting said connection through a variable portion of the displacing stroke of said impulse piston; and means for adjusting said adjustable means.

6. The combination of a compressor having a cylinder and a coacting piston; unloading means for said compressor; an unloader piston for actuating said unloading means; an impulse piston actuated in timed relation to the compressor piston and having a displacement which exceeds the displacement of the unloader piston; means for establishing a liquid pressure transmitting connection between the impulse piston and the unloader piston; a pressure accumulator; a loaded relief valve for permitting flow of excess liquid under pressure from said connection to said accumulator; adjustable means operated in timed relation with the impulse piston for freely venting said connection through a variable portion of the displacing stroke of said impulse piston; a servo motor operated by pressure from said accumulator, connected to adjust said adjustable means and including a valve which controls its motion; and means for shifting the last-named valve.

7. The combination of a compressor having a cylinder, a coacting piston and an inlet valve; means for unloading said compressor by controlling the action of the inlet valve; an unloader piston for controlling said unloading means; an impulse piston actuated in timed relation to the compressor piston and having a displacement which exceeds the displacement of the unloader piston; means for establishing a hydraulic pressure transmitting connection between the impulse piston and the unloader piston; a pressure accumulator; a loaded relief valve for permitting flow of excess hydraulic liquid under pressure from said connection to said accumulator; adjustable means operated in timed relation with the impulse piston for freely venting said connection through a variable portion of the displacing stroke of said impulse piston; a servo-motor operated by pressure from said accumulator, connected to adjust said adjustable means and including a valve which controls its motion; and means for shifting the last-named valve.

8. The combination of a compressor having a cylinder, a coacting piston and an inlet valve; shiftable means having an inactive position, and an active position in which it serves to hold the inlet valve open; means biasing the last-named means to its active position; an unloader piston for forcing the means which holds the inlet valve open to its inactive position; an impulse piston actuated in timed relation to the compressor piston and having a displacement which exceeds the displacement of the unloader piston; means for establishing a hydraulic pressure transmitting connection between the impulse piston and the unloader piston; a pressure accumulator; a loaded relief valve for permitting flow of excess hydraulic liquid under pressure from said connection to said accumulator; adjustable means operated in timed relation with the impulse piston for freely venting said connection through a variable portion of the displacing stroke of said impulse piston; a servo-motor operated by pressure from said accumulator, connected to adjust said adjustable means and including a valve which controls its motion; and means for shifting the last-named valve.

14. The combination of a compressor having a cylinder and a coacting piston; unloading means for said compressor; an unloader piston for actuating said unloading means; an impulse piston actuated in timed relation to the compressor piston and having a displacement which exceeds the displacement of the unloader piston; means for establishing a hydraulic pressure transmitting connection between the impulse piston and the unloader piston; a pressure accumulator; a loaded relief valve for permitting flow of excess hydraulic liquid under pressure from said connection to said accumulator; adjustable means operated in timed relation with the impulse piston for freely venting said connection through a variable portion of the displacing stroke of said impulse piston; a servo-motor of the differential piston type including a balanced distributing valve, said servo-motor being operated by pressure fluid derived from said accumulator and being connected to actuate said adjustable means; and means for shifting said balanced distributing valve in response to variations of pressure developed by the operation of the compressor.

15. The combination of a compressor having a cylinder and a coacting piston; unloading means for the compressor; an unloader piston arranged to actuate said unloading means; an impulse piston actuated in timed relation to the compressor piston and having a displacement which exceeds the displacement of the unloader piston; means for establishing a hydraulic pressure transmitting connection between the impulse piston and the unloader piston; a loaded relief valve permitting flow of excess hydraulic liquid from said connection; a combined inlet and spill-back valve for permitting flow of liquid to and from said connection; an adjustable actuating connection between the impulse piston and the last-named valve for holding the valve open during a variable portion of the displacing stroke of the impulse piston; and means for adjusting said connection.

16. The combination of a compressor having a cylinder and a coacting piston; unloading means for the compressor; an unloader piston arranged to actuate said unloading means; an impulse piston actuated in timed relation to the compressor piston having a displacement which exceeds the displacement of the unloader piston; means for establishing a hydraulic pressure transmitting connection between the impulse piston and the unloader piston; a loaded relief valve permitting flow of excess hydraulic liquid from said connection; a pressure accumulator fed thereby; a combined inlet and spill-back valve for permitting flow of hydraulic liquid to and from said connection; an adjustable actuating connection between the impulse piston and the last-named valve for holding the valve open during a variable portion of the displacing stroke of the impulse piston; means for adjusting said actuating connection; a servo-motor fed by said accumulator and connected to actuate said adjusting means, said servo-motor including a pilot valve; and means responsive to a variable pressure established by said compressor for shifting said pilot valve.

17. The combination of a compressor having successive operating cycles; liquid displacing means for developing liquid pressure impulses in timed relation to the operating cycles of the compressor; means operable while the compressor is running for varying the duration of such impulses; and unloading means controlled by

said impulses, and serving to unload the compressor to a degree which varies with the duration of such impulses.

18. The combination of a compressor having successive operating cycles; liquid displacing means for developing liquid pressure impulses in timed relation to the operating cycles of the compressor; adjustable venting means adjustable while the compressor is running for varying the duration of such impulses; and unloading means controlled by said impulses, and serving to unload the compressor to a degree which varies with the duration of such impulses.

19. The combination of a compressor having a working space in which recurrent compression cycles are performed; an inlet valve of the suction operated type for such working space; pressure shiftable means for alternately permitting and suspending the normal operation of such inlet valve; at least one displacing means operated in timed relation with the compression cycles of the compressor to develop pressure impulses in said pressure shiftable means; adjustable venting means for varying the duration of such impulses; and means operable while the compressor is running for adjusting the last-named means.

20. The combination of a compressor having a working space in which recurrent compression cycles are performed; an inlet valve of the suction operated type for such working space; pressure shiftable means for alternately permitting and suspending the normal operation of such inlet valve; displacing means operated in timed relation with the compression cycles of the compressor to develop pressure impulses in said pressure shiftable means; adjustable venting means for varying the duration of such impulses; an accumulator arranged to receive excess pressure fluid delivered by said displacing means; a servo-motor fed by said accumulator and connected to adjust said venting means, said servo-motor including a pilot valve which controls its action; and means responsive to variations of pressure developed by operation of the compressor for shifting said pilot valve.

21. The combination of a compressor of the expansible chamber type adapted to perform successive operating cycles; an unloading device having two positions, in one of which it renders the compressor inoperative and in the other of which it renders it operative; means biasing said unloader toward one of said positions; a pressure motor serving when energized to shift said unloader to the other of said positions; an impulse piston actuated in timed relation to the cycles of the compressor; means establishing a fluid pressure transmitting connection between said impulse piston and said pressure motor; adjustable means for venting said connection throughout a variable portion of the displacing stroke of said impulse piston; and means operable to vent said connection continuously.

22. The combination of a compressor of the expansible chamber type adapted to perform successive operating cycles; an unloading device having two positions, in one of which it renders the compressor inoperative and in the other of which it renders it operative; means biasing said unloader toward one of said positions; a pressure motor serving when energized to shift said unloader to the other of said positions; an impulse piston actuated in timed relation to the cycles of the compressor; means establishing a fluid pressure transmitting connection between said

impulse piston and said pressure motor; adjustable means for venting said connection throughout a variable portion of the displacing stroke of said impulse piston; means responsive to the pressure established by the operation of the compressor for adjusting the last-named means; and means operable to vent said connection continuously.

23. The combination of a compressor having a cylinder, a coacting piston and an inlet valve; shiftable means adapted to obstruct the closing movement of the inlet valve; means biasing said shifting means toward obstructing position; an unloader piston operable to withdraw said obstructing means; an impulse piston actuated in timed relation to the compressor piston and having a displacement which exceeds the displacement of the unloader piston; means for establishing a hydraulic pressure transmitting connection between the impulse piston and the unloader piston; a loaded relief valve permitting flow of excess hydraulic liquid from said connection; adjustable means operating in timed relation with the impulse piston for freely venting said connection through a variable portion of the displacing stroke of said impulse piston; means for adjusting said adjustable means; and means operable to vent said connection continuously.
24. The combination of a compressor having a cylinder, a coacting piston and an inlet valve; means for holding the inlet valve open; means biasing the last-named means to its active position; an unloader piston for forcing the means which holds the inlet valve open to its inactive position; an impulse piston actuated in timed relation to the compressor piston and having a displacement which exceeds the displacement of the unloader piston; means for establishing a hydraulic pressure transmitting connection between the impulse piston and the unloader piston; a pressure accumulator; a loaded relief valve for permitting the flow of excess hydraulic liquid under pressure from said connection to said accumulator; adjustable means operated in timed relation with the impulse piston for freely venting said connection through a variable portion of the displacing stroke of said impulse piston; a servo-motor operated by pressure from said accumulator, connected to adjust said adjustable means and including a valve which controls its motion; means for shifting the last-named valve; and means operable to vent said accumulator continuously.
25. The combination of a compressor having successive operating cycles; liquid displacing means for developing liquid pressure impulses

having successive ineffective and effective portions; means operable while the compressor is running for varying the timing of the effective portion of such impulses with respect to the operating cycles of the compressor; and capacity controlling means controlled by said impulses and serving to vary the capacity of the compressor in accordance with such timing.

26. The combination of a compressor having a working space in which recurrent compression cycles are performed; an inlet valve of the suction operated type for such working space; pressure shiftable means for alternately permitting and suspending the normal operation of such inlet valve; at least one displacing means operated in timed relation with the compression cycles of the compressor to develop pressure impulses in two phases, one of which phases is ineffective, and the other of which phases is effective to actuate said pressure shiftable means; means effective to vary the point in the compression cycle of the compressor at which said change of phase occurs; and means operable while the compressor is running for controlling the last-named means.

27. The combination of a compressor having successive operating cycles each comprising a suction stroke and a displacement stroke; liquid displacing means for developing successive hydraulic pressure impulses one for each cycle, said means being capable of developing such impulses over the entire displacement stroke; means operable while the compressor is running for varying the point in the displacement stroke at which such impulse is initiated; and means for unloading said compressor during the displacement stroke until said impulse is initiated and for thereafter loading the compressor throughout the remainder of the stroke.

28. The combination of a compressor of the expansible chamber type adapted to perform successive operating cycles; an unloading device having two positions, in one of which it renders the compressor inoperative and in the other of which it renders it operative; means biasing said unloader toward one of said positions; a pressure motor serving when energized to shift said unloader to the other of said positions; an impulse piston actuated in timed relation to the cycles of the compressor; means establishing a fluid pressure transmitting connection between said impulse piston and said pressure motor; and adjustable means for varying the time of commencement of the impulses produced by said piston relatively to the cycle of the compressor.
